UNITED STATES PATENT OFFICE.

ANTONY LASKI, OF NEW BRITAIN, CONNECTICUT, ASSIGNOR, BY DIRECT AND MESNE ASSIGNMENTS, OF ONE-FOURTH TO THEODORE DUDJAK, ONE-FOURTH TO BERNARD MILLER, AND ONE-FOURTH TO AUGUSTYN MORRIS, ALL OF NEW BRITAIN, CONNECTICUT.

HINGE-BUTT.

1,003,618.

Specification of Letters Patent. Patented Sept. 19, 1911.

Application filed June 2, 1911. Serial No. 630,749.

To all whom it may concern:

Be it known that I, ANTONY LASKI, a citizen of the United States, residing at New Britain, in the county of Hartford and 5 State of Connecticut, have invented certain new and useful Improvements in Hinge-Butts, of which the following is a specification.

My invention relates to improvements in 10 hinge butts and the objects of my improvement are to produce a hinge butt that is made up of two leaves that are united in such a way as to be non-separable when the door to which the same is applied is closed 15 and which is provided with means that prevent the separation of the leaves when the door is open, and which feature permits of the use of my hinge butt with the joint for the two leaves exposed and on the outside 20 of the building and without danger to the security of the building.

Other objects will appear from a consideration of the details of construction.

In the accompanying drawing:—Figure 1 25 is a front elevation of my improved hinge butt. Fig. 2 is a reverse view of the same. Fig. 3 is a sectional view on the line *x-x* of Fig. 1. Fig. 4 is a plan view of one of the bearing members. Fig. 5 is a side elevation of the same. Fig. 6 is a bottom view of the same. Fig. 7 is a sectional view on the line *y-y* of Fig. 3.

A is a hinge butt comprising a pair of leaves respectively a left leaf B and a right leaf C, united by a hinge connection in accordance with my invention. The said leaves B and C comprise each a leaf proper 10 of the usual plate like form suitable for being secured to the door or casing provided with screw holes 11, and along one edge provided with knuckles to be described. The said left leaf B comprises a single elongated knuckle 12 which is a fit for the space between the pair of knuckles 13 that are provided for the right leaf C. The said intermediate knuckle 12 on the left leaf B is generally solid, and has at the ends a socket or bed 14, which may be semi-spherical as shown or of some other formation suitable 45 for receiving a ball D. The said end knuckle 13 on the right leaf C is exteriorly of the same size as the intermediate knuckle 12, and cylindrical in shape, and interiorly is

provided with an axial bore 15 which is of a diameter such as to admit the said ball 55 D, and the outer end of which bore 15 is provided with a screw thread 16. The said knuckle 13 is also provided with a radial threaded hole 17 for a set screw E, and which is preferably located inwardly from 60 the said screw threaded portion 16 of the bore 15. A cylindrical bearing member G that is fitted to the said bore 15, has the outer end 18 generally flat and provided with a pair of depressions 19 leaving between them a central bridge 20 that is suitable for a handle for manipulating the said bearing member G, and at the inner end is provided with a bearing socket or bed 21, which is the counterpart of the said bed 14 70 and suitable to coöperate therewith to operatively house the said ball D. The length of the said bearing member G may be such that the said outer end 18 will abut against a holding screw H engaged with the said 75 thread 16 and be held thereby in proper position to operatively house the said ball D as described. A radial socket or recess 22 may be provided that registers with the radial slot screw hole 17 and is suitable for receiving the end of the said set screw E. The said holding or end screw H comprises a screw threaded body 23 which is fitted to the said screw threaded outer end 16 of the bore 15 and is of length sufficient to abut 85 against the said bearing member G as described, and is provided with an overhanging head 24, which may be ornamental as shown, and has the annular shoulder 25 suitable for engaging with the outer end 26 of 90 the said outer knuckle 13, and thereby positively limit the position of the bearing member G in the bore 15.

In assembling my hinge butt the leaves B and C are brought into position such that 95 the intermediate knuckle 12 is located between the end knuckles 13 and in axial alignment therewith and then the upper ball D is dropped through the upper bore 15 into the upper bed 14. After this has been done, 100 the said upper ball D will operate to hold the leaves B and C together so as to facilitate the other operations in assembling. The upper bearing member G may next be inserted in the bore 15, and the set screw E 105 screwed into the socket 22 provided there-

for and which operates to properly position the said bearing member G. The upper holding screw H is next inserted in the upper threaded end 16, and screwed home, the 5 flange 25 abutting against the upper end 26 of the upper knuckle 13 and the inner end 27 in abutment with the opposed outer end 18 of the bearing member G. The bridge 20 facilitates placing the said bearing member G in proper position in the operations 10 described, particularly in regard to the feature of the registration of the socket or recess 17 and the set screw E, and the said bridge also facilitates the removal of the 15 said upper bearing member G, in which operation the operations described are reversed. The assembly of the lower member of the hinge joint corresponds to that of the upper member in the arrangement of 20 the elements and final positioning of the same, though the manipulation of the said elements is essentially different from the fact that the several parts are raised in bringing them home, and that the lower 25 ball D and the lower bearing member G must be held in their proper positions until the bearing member G is positively held by either the set screw E or the lower holding screw H. It will be noted that the location 30 of the said radial screw hole 17 is such that access to the said set screw E contained therein is only possible when the hinge A is open, as shown in Fig. 1, and in the closed position the said set screws E, 35 which as shown are carried by the right leaf C, are turned so as to be covered by the leaf proper 10 of the mating or left hand leaf B. Accordingly, in the closed position, the set 40 screw E is not removable. In all positions, the balls D, which operate as pintles, prevent the lateral separation of the hinge members B and C, and on account of the limiting feature described in regard to the removal of the set screws E, my hinge members 45 are non-separable in all positions except the open position, and of course are non-separable in the closed position. Therefore it is possible to install my hinge 50 butt in position and with the joint, or knuckle members exposed on the outside of the building, and without danger to the security of the building. On this account my hinge butt is suitable for use on public buildings, and with the knuckles exposed as 55 described, so as to permit the doors to open outward, a feature that is desirable and gen-

erally insisted upon in regard to such buildings.

I claim as my invention:—

1. In a hinge comprising a pair of hinge members having knuckles pivotally united by balls operative as pintles and having means for removing the said balls, a set screw operative to permit such removal, and means for covering the said set screw and to prevent such removal and separation of the hinge members when the said hinge members are in the closed position. 60

2. A hinge comprising an intermediate knuckle and a pair of end knuckles, the said intermediate knuckle having a bed for a ball at each end, the said end knuckles each provided with an axial bore, a bearing member fitting said bore, and provided at one end with a bed suitable for co-operating with the said first bed for operatively housing a ball, and means for retaining the said bearing member in the said bore. 70

3. A hinge member comprising an intermediate knuckle and a pair of end knuckles, 80 a bed for a ball provided at each end of the said intermediate knuckle, the said end knuckles having each an axial bore, and having a thread at the outer end, a bearing member fitting the said bore and housed 85 therein, and a holding screw engaged with the said thread and holding the said bearing member in the said bore.

4. A hinge member comprising a pair of mating leaves, each of the said leaves having 90 a leaf proper, an intermediate knuckle member integral with one, and a pair of end knuckle members integral with the other of the said leaves proper, the said intermediate knuckle comprising a bed for a ball 95 at each end, the said end knuckles having an axial bore, and having a thread at the outer end thereof, a bearing member housed within the said axial bore, and having a bed at the inner end, a holding screw engaged 100 with the thread and operative to hold the said bearing member longitudinally in the said bore, a ball operatively housed between each end of the said intermediate knuckle and an end knuckle and in the said beds, and 105 a set screw penetrating the lateral wall of the said end knuckles and engaged with the said bearing member.
